METAL FABRICATION

Arthur F. Johnson, Boulder, Colo., assignor to Olin Mathieson Chemical Corporation, East Alton, Ill., a corporation of Virginia
Original application Apr. 7, 1955, Ser. No. 499,956, now Patent No. 2,915,296, dated Dec. 1, 1959. Divided and this application Apr. 13, 1959, Ser. No. 809,334 13 Claims. (Cl. 29—157.3)

This invention relates generally to metal fabrications and more particularly to a novel heat exchanger. This application is a division of pending application Serial No. 499,956, filed April 7, 1955, now Patent No. 2,915,296.

In manufacturing liquid to air type heat exchangers it is desirable to use the least amount of metal possible to achieve the area of heat exchange surface required to transfer the heat from the liquid to the air. Heat exchangers of this type ordinarily have a tube containing the liquid to be cooled and a plurality of fins extending radially therefrom. The transfer of a given amount of heat from metal to air requires a much larger surface area than is required to transfer the same amount of heat from the liquid to the metal. Consequently, the fins ordinarily make up the larger part of the heat exchanger. The ultimate cost of the heat exchanger is thus largely dependent upon the amount of metal required to provide sufficient fins to achieve the proper heat transfer from the fins to the air.

Therefore, an object of this invention is to provide a heat exchanger with a novel fin having improved heat transfer properties. Another object of this invention is to provide heat exchange units having fins constructed from metals or alloys which have inferior specific heat conductivity but are economically advantageous. Another object of this invention is to provide a fin for heat exchangers having an improved means for conducting the heat from a liquid to air. Still another object of this invention is to provide a liquid to air heat exchanger having fins adapted to more efficiently transfer heat from a confined fluid into the surrounding air. A still further object of this invention is to provide a method for making liquid to air heat exchangers.

Other objects will become apparent from the following detail description and the attached drawing in which

FIGURE 1 illustrates in a perspective view an assembly of metal sheets suitable for forming a fin for heat exchangers in accordance with an embodiment of this invention;

FIGURE 2 is a plan view of the assembly of FIGURE 1 after welding;

FIGURE 3 is a cross-sectional view taken along the line A—A of FIGURE 2;

FIGURE 4 illustrates a fragmentary elevational view of the embodiment of FIGURE 2 after inflation;

FIGURE 5 is a fragmentary perspective view partially in section along the line B—B of FIGURE 4 illustrating the step of filling the hollow channel of the assembly;

FIGURE 6 illustrates an embodiment of this invention such as can be formed from the panel of FIGURE 4;

FIGURE 7 illustrates in a perspective view an assembly of two metal sheets prepared for welding to form another embodiment of this invention;

FIGURE 8 illustrates an embodiment of this invention formed from an assembly like that of FIGURE 7;

FIGURE 9 is a cross-sectional view illustrating the embodiment of FIGURE 8;

FIGURE 10 is a cross-sectional view of an embodiment of this invention formed from three sheets of metal; and

FIGURE 11 illustrates still another embodiment of the invention.

In accordance with this invention, the foregoing objects

2

as well as others are accomplished, generally speaking, by providing a heat exchanger fin having a tubular circuit containing a fluid refrigerant extending from the heated portion of the fin to the portion in the cooling medium. 5 The circuit or conduit is of such configuration that the fluid contained therein can circulate from a point adjacent the heated liquid to the outer edge of the fin and back either entirely in the liquid phase or in both liquid and vapor phases. The conduit may extend around the edges 10 of the fin or it may be of such configuration that one portion thereof extends along the hotter edge of the fin and another portion extends along the colder edge with radially extending portions connecting the two together. The outer edge of the fin is at a greater elevation than the edge 15 adjacent the tube containing the heated liquid in order that the confined fluid after cooling by the air or other medium in contact with the fin can return by gravity to that portion of the conduit adjacent the heated liquid. Any suitable fluid may be used but for most purposes a fluid having 20 a boiling point less than that of the liquid to be cooled is preferred so that cooling may be accomplished at least partly by phase transitions in the fluid between the liquid and vapor phases.

In practice, the high boiling point liquid which is to be 25 cooled is flowed through a tube or other means having attached thereto the fins of this invention. Ordinarily, a plurality of the fins are utilized and the upper surface of each of the fins forms an acute angle with the tube. The conduit of each fin is only partially filled with the 30 fluid. As stated above, it is preferred that the refrigerant have a boiling point less than that of the liquid to be cooled in order that it will be heated above its boiling point. This sets up a circulation in the conduit and the heated and less dense fluid flows towards the outer edge of 35 the fin where it is cooled. The more dense, cooler fluid flows by gravity back towards the inner edge of the fin adjacent the heated liquid where it again absorbs heat and the process is repeated. Since the fluid expands with increase in temperature, and particularly at its boiling point, 40 it is advantageous in some embodiments to make the portions which will contain the heated fluid of greater volume than those portions containing the fluid after it has been cooled. A conduit of gradual tapering width accomplishes this purpose by locating the wider portion near the heated 45 tube and the narrower portion along the opposite edge of the fin. If only one tubular portion extends radially across the fin the fluid may be refluxed with the cooler fluid flowing back into the boiler portion of the conduit for reheating. When cooling by transition from the liquid to the 50 vapor phase of the fluid is contemplated a waffle pattern containing multiple conduits may sometimes be advantageous.

In order better to describe and further clarify the invention the following is a detail description of embodiments thereof with reference to the accompanying drawing:

Superposed aluminum sheets 1 and 2 having a pattern of a suitable stop weld 3 sandwiched therebetween are illustrated in FIGURE 1. Each of the sheets is degreased 55 by immersing it in an organic solvent such as naphtha or white gasoline, any oxide clinging thereto is removed by scratch brushing and a pattern of stop weld 3 is applied before the sheets are assembled. Stop weld 3 may conveniently be composed of a mixture of about 13% colloidal graphite, about 40% calcium carbonate having a granulation of about 325 mesh or less and about 47% water. The two sheets are assembled by lying one on the other in face to face relationship and are fastened together by spot welding or other means in areas not 60 covered by stop weld 3.

The resulting assembly of sheets 1 and 2 is heated in a suitable furnace to about 1000° F. in a reducing atmos-

phere and while at this temperature the assembly is passed through a rolling mill to reduce its thickness about 60%.

Those contacting surfaces of sheets 1 and 2 not protected by stop weld 3 are thus forge welded together. The assembly may be rolled later at room temperature to the final gauge. In some embodiments, of course, the cold rolling step may not be required although it has been found that a cold rolling step is advantageous when it is necessary to control the final dimensions of the assembly to close tolerances.

The unwelded portions lying within the assembly are inflated by means of fluid pressure. As illustrated in FIGURE 2 a hole 4 is drilled in the assembly adjacent the unwelded area and a suitable needle or similar device 33, in FIGURE 3, is inserted in hole 4 and compressed air is applied therethrough. A panel such as derived from the assembly of FIGURES 1, 2 and 3 is illustrated in FIGURE 4. The conduit resulting from the inflation is designated generally as 5 and the surface of the panel is designated generally as 6.

The passageway or hole 4 is also utilized in filling the conduit 5 with a fluid refrigerant. A needle or similar somewhat pointed instrument illustrated as 7 in FIGURE 5 is inserted through hole 4 into the conduit and the desired amount of fluid, such as, ethyl alcohol, is allowed to flow in by gravity or it may be pumped in, if desired. The needle 7 should be of such dimensions that the air displaced by the fluid in the conduit can escape through hole 4. Conduit 5 is only partially filled with a fluid in order to compensate for expansion of the fluid when heated. When the fluid chosen undergoes phase transition from a vapor to a liquid a relatively large condensation area is needed.

After the liquid has been introduced into conduit 5 hole 4 is plugged by soldering, brazing, cold welding or other suitable processes to complete the fabrication of the circuit through which the fluid will flow. The resulting panel is then welded, brazed or attached by any other suitable means to a tube or other container adapted to contain the heated liquid in the heat exchanger. Such a tube is illustrated as 8 in FIGURE 6 and has a fin such as is formed from the panel of the preceding figures. Conduit 5 in this fin is of greater dimensions in those areas which will contain the heated fluid than in the other areas of the circuit. The direction of flow of fluid in conduit 5 is illustrated with arrows in FIGURE 6.

It is also possible to form the heat exchanger tube and fins by a forge welding process similar to that described in the foregoing. In such a process two aluminum sheets 11 and 12 in FIGURE 7 are cleaned as described in conjunction with the foregoing embodiment and two patterns of stop weld 13, similar to pattern 3 of the foregoing embodiment, are applied to the surface of one sheet. A band of stop weld 14 is applied to one surface of one of the sheets bisecting the sheet and extending almost throughout its length such as illustrated in FIGURE 7. This assembly is heated, forge welded by rolling to reduce its thickness at least 65 percent and otherwise processed in accordance with the process described above and the conduits are expanded by drilling a hole in the resulting assembly to provide an entrance to the unwelded areas bordering the patterns of stop weld 13. As indicated in the drawing the band of stop weld 14 terminates short of the edges of the assembly except that a narrower band 15 at one end thereof extends to the edge of the sheet. This unwelded portion bordering stop weld 15 is pried apart, a suitable needle is inserted and the unwelded area bordering 14 is thereafter inflated by means of fluid pressure. The assembly is then trimmed along its edges to remove the passageway resulting from 14 so that the passageway resulting from 14 extends entirely through to provide a tube 19 with fins 20 and 21 similar to those as illustrated in FIGURE 8. The integral fins 20 and 21 have conduits 22 and 23 and are filled with fluid refrigerant substantially as described in conjunction with

the foregoing embodiments. A cross-sectional view of a fin and tube arrangement of the type illustrated in FIGURE 8 is shown in FIGURE 9.

A variation in the type of design that can be made in accordance with this invention is illustrated in FIGURE 10. In this particular embodiment three clean sheets of aluminum are utilized and patterns of stop weld are sandwiched between each pair of contacting surfaces of the resulting assembly of three sheets. The assembly is forge welded by hot rolling to reduce the thickness of the assembly about 65 percent and the unwelded areas protected by the stop weld are inflated by means of fluid pressure to produce a central tube 19 having fins 20 and 21. Each of the fins has two conduits, one on each side thereof. The center sheet of the assembly of three sheets forms a partitioning member between the pair of conduits lying on each side of the fin. In the embodiment shown in FIGURE 10 the upper conduit of fin 20 is designated as 24 while the upper conduit of fin 21 is 25. The lower conduit of fin 20 is illustrated as 26 and the lower conduit of fin 21 is designated 27. It is to be noted that the fins are bent to form an acute angle with the axis of the tube in order that gravity can be utilized for return of the cooled liquid from the outer edge of the fin to that portion of the conduit adjacent tube 19. Tube 19 in this instance is in a horizontal position.

The embodiment illustrated in FIGURE 11 is a circular fin extending around the tube 28 which contains the heated liquid. This fin has a plurality of conduits having a portion 31 adjacent the heated tube 28, a portion 29 adjacent the cooler edge 32 and a radially extending portion 30 connecting portions 31 and 29. Edge 32 of the fin is at a higher elevation than the edge adjacent tube 28. In operation, the liquid confined in the conduit is heated to the boiling point and moves towards portion 29. It condenses there and flows back through the radially extending portion 30 to portion 31. The dimensions of the portions 29 and 31 can, of course, be varied but the greater the size thereof the greater the heat transfer in some instances. In some embodiments the portion 29 may be of no greater length than the width of the portion 30.

In the foregoing embodiments the fins are formed from aluminum. For some purposes it might be more desirable to form the fins from copper or copper-base alloys or ferrous alloys. Indeed the invention contemplates forming the fins from any suitable metal. Although it is advantageous to form the fins from sheet metal by forge welding as described in the foregoing it is, of course, possible to use other welding methods for forming the conduits on the surface of the fins. For example, the raised portion might be stamped from a sheet of metal and thereafter brazed or otherwise fastened to the surface of the fin to form a conduit. From the practical standpoint, however, the forge welding method with subsequent inflation by fluid pressure is favored. The assembly illustrated in FIGURE 8 is particularly advantageous because the fins are integral with the tube and thus the heat transfer characteristics are improved over a structure where it is necessary to weld or otherwise connect the fin to the surface of the tube. A plurality of assemblies of this type can be arranged to form heat exchangers having a tube following a serpentine path with fins extending therefrom. The heat exchanger of this invention is particularly useful for making automobile radiators or other heat exchangers where it is desirable to transfer the heat from a liquid to air.

In one application the fins of this invention can be attached to a cylinder suitable for use in internal combustion engines and it is possible to eliminate the radiator usually required for cooling such engines. Because of the improved heat transfer characteristics of the fins it is possible to air cool the cylinders. In forming an assembly of cylinders and fins a mold can be formed by stacking aluminum fins one on the other with a suitable washer

interposed between each pair of fins. This assembly is clamped together and a cylindrical cast iron member suitable to serve as a cylinder wall is placed inside the resulting cavity. Molten aluminum is then poured between the external wall of this cast iron cylinder and the wall formed by the alternate aluminum fin edges and washer edges. Upon solidification, the edges of the fins are welded to the aluminum cylindrical wall and the cast iron cylinder serves as a liner for the cylinder.

In another application of this invention similar to the foregoing the fins are made of rust resistant sheet iron and the spacing washers are of the same material. The cast iron cylinder is formed by pouring molten cast iron in a suitable mold, the outer wall of which is constituted by the fins and spacers to which the molten cast iron firmly attaches itself.

By choosing the proper fluid and gas pressure in the conduit the cylinder temperature can be held at the most efficient temperature. In automobiles this temperature may be above 212° F. By sealing nitrogen in the circuit at 60 lbs. gage pressure with water, boiling of the water will not occur until about 290° F. so temperature of the auto cylinder and fin would tend to stabilize at this temperature. Very pure water containing corrosion inhibitors may be used. Also chemicals such as ethylene glycol and the like may be added to prevent freezing.

As indicated hereinbefore it is desirable that that portion of the conduit which is to contain the captive fluid after cooling should be at an elevation greater than that portion which contains the heated captive fluid. In this way the cooler fluid will more readily flow from the edge of the fin to that portion adjacent the tube containing the heated liquid. Circulation within the conduit is also brought about by boiling of the fluid in the conduit. For this reason the fluid contained in the conduit should preferably have a boiling point less than the boiling point of the liquid in the heat exchanger tube. For example, if water is to be cooled the conduit may advantageously contain ethyl alcohol or a mixture of this and water.

As an illustration of an advantage of this invention, aluminum has a specific heat of 0.2 calories per gram per degree centigrade temperature rise while copper has a specific heat of 0.1. If it is desired to keep the boiling point of a liquid in the heat exchanger tube, such as that illustrated as 19 in FIGURE 8, at a temperature between that of boiling water (100° C.) and the boiling point of ethyl alcohol (about 78° C.), ethyl alcohol may be used in the conduit and each gram of alcohol boiled in the portion of the conduit adjacent tube 19 will carry away to the extremities of the fin as much heat as would be required by raising 1020 grams of aluminum 1° C. in temperature. If copper is utilized for the fin instead of aluminum 2040 grams of copper would be required for a similar increase of 1° C. Thus the heat exchanger fin having the enclosed circuitous conduit containing a fluid permits the use of a fin with much less weight to preserve the same minimum of temperature differential between heated and cooled portions of the fin.

The configuration of the conduit may be such that a turbulent gas flow between adjacent fins is introduced without impairing the principal function of the cooling liquid. In assembling several fins together to form a heat exchanger the inflated portions forming the conduit would be alternated in position in order to cause a turbulence of the air as it passes between the fins. It is apparent from the foregoing that the fin of this invention can be assembled to tubes with a minimum number of brazed joints which is, of course, advantageous not only from the standpoint of manufacturing costs but also with respect to the life of the heat exchangers. Although ethyl alcohol or its mixtures with water are particularly well suited in the fins for cooling heated water any other suitable fluid such as methyl alcohol, glycerine, ethylene glycol, water or its mixtures with the foregoing, xylene, or the like may be utilized. The stop weld composition given

in the foregoing is particularly well suited for aluminum but other compositions such as mixtures of colloidal graphite and sodium silicate can be utilized. The amount of reduction in the forge welding process will vary depending upon the particular metal utilized but will ordinarily fall within the range of from 35% to about 65%.

Although embodiments of the invention have been described in considerable detail in the foregoing it is to be understood that modifications can be made therein by those skilled in the art without departing from the spirit or scope of the invention except by the scope of the appended claims.

What is claimed is:

1. A method for making heat exchangers which comprises cleaning the to-be-superimposed surfaces of a plurality of metal sheets, placing a band of stop weld on the said cleaned surface of one of the sheets in a pattern adjacent the four edges thereof defining a circuitous system of tubular passageways circumscribing said heat exchanger, said pattern being coextensive with and spaced from the said edges, forming an assembly by superimposing the cleaned surface of another of said sheets adjacent said stop-weld coated surface, heating the assembly and forge welding by hot rolling the adjacent surfaces 20 of said assembly together in the areas not separated by said stop-weld material, forming an inlet into the unwelded areas defined by said stop-weld material, inflating the unwelded areas by means of fluid pressure injected through said opening, injecting a fluid in the resulting 25 passageway, sealing the hole through which the injection was made to seal said fluid in said system of passageways, and thereafter attaching the resulting panel having a conduit containing the fluid to a heat exchanger tube.
2. A method for making a heat exchanger which comprises cleaning two metal sheets, applying two separate narrow circuitous patterns of stop weld on the surface of the sheets and a separate narrow band of stop weld along one axis of said sheet which bisects the same and lies between the aforesaid pair of patterns, said stop-weld material being applied so that each of said patterns defines a circuitous system of tubular passageways extending through said heat exchanger in a closed circuit circumscribing a portion of said heat exchanger, welding the face to face portions of the sheet unprotected by the stop weld, inflating the unwelded areas, injecting a heat 35 exchange fluid in the circuitous conduits resulting from the inflation of the unwelded areas adjacent the aforesaid circuitous patterns of stop weld, and sealing said fluid in said circuitous conduits.
3. A method of making a plate-like secondary heat exchanger in heat exchange relationship with a primary heat exchanger comprising forming said secondary heat exchanger by sandwiching between pressure weldable surfaces of superposed flat sheets a pattern of stop-weld 40 material defining a circuitous system of fluid passageways extending in a closed circuit circumscribing at least one portion of said secondary heat exchanger, pressure welding said sheets together in their adjacent areas not separated by said stop-weld material, forming an inlet into the unwelded portions of said sheets in the areas defined by said stop-weld material, inflating said unwelded area by means of fluid pressure applied through said opening to form said system of passageways, injecting a heat exchange fluid through said opening into said system of 45 passageways, sealing said opening to seal said heat exchange fluid in said system of passageways, and placing said secondary heat exchanger in heat exchange relationship with said primary heat exchanger.
4. The method of claim 3 wherein said fluid partially fills said passageways and is vaporizable and condensable.
5. The method of claim 3 wherein said pattern is applied to define said system of passageways to comprise at least three tubular passageway portions extending in at least three directions serially connected to each other at their ends to form said closed conduit circuit.

6. The method of claim 5 wherein said fluid partially fills said passageways and is vaporizable and condensable.

7. The method of claim 3 wherein said system of passageways is applied adjacent the edges of said sheets to define a system of passageways comprising a continuous tubular portion coextensive with and spaced from said edges.

8. A method of making a plate-like secondary heat exchanger in heat exchange relationship with a primary heat exchanger comprising sandwiching between pressure weldable surfaces of superposed flat metal sheets a first pattern and separate independent second pattern of stop-weld material, said first pattern being applied to define desired tubular passageways for flow of a primary heat exchange fluid therethrough and said second pattern being applied to define a circuitous system of tubular passages extending between said sheets in a closed circuit circumscribing at least one portion of said sheets, pressure welding said sheets together in the areas not separated by said stop-weld material, forming an opening into the unwelded areas between said sheet defined by said second pattern of stop-weld material, applying through said opening a fluid pressure of sufficient magnitude to expand said unwelded area defined by said second pattern of stop-weld material, injecting through said opening a secondary heat exchange fluid to at least partially fill said unwelded area, and sealing said opening to seal said secondary heat exchange fluid in said unwelded area.

9. The method of claim 8 wherein said secondary heat exchange fluid partially fills said unwelded area and is vaporizable and condensable.

10. A method of making a plate-like heat exchanger comprising forming said heat exchanger by sandwiching between pressure weldable surfaces of superimposed flat sheets a pattern of stop-weld material defining a system of fluid passages adapted to form a closed system of said passages containing a fluid under pressure, pressure welding said sheets together in their adjacent areas not separated by said stop-weld material, forming an inlet into the unwelded portions of said sheets in the areas defined by said stop-weld material, inflating said unwelded areas by means of fluid pressure applied under sufficient pressure through said opening to form said system of passageways, injecting a heat exchange fluid through said opening into said system of passageways, sealing said opening to form a closed system of said passageways containing said heat exchange fluid.

11. A method of making a plate-like secondary heat exchanger in heat exchange relationship with a primary heat exchanger comprising forming said secondary heat exchanger by sandwiching between pressure weldable surfaces of superimposed flat sheets a pattern of stop-weld

material defining a system of fluid passageways adapted to form a closed system of said passages containing a heat exchange fluid with at least one of said sheets adapted to be placed in heat exchange relationship with said primary heat exchanger, pressure welding said sheets together in their adjacent areas not separated by said stop-weld material, forming an inlet into the unwelded portions of said sheets in the areas defined by said stop-weld material, inflating said unwelded areas by means of fluid pressure applied under sufficient pressure through said opening to form said system of passageways, injecting a heat exchange fluid through said opening into said system of passageways, sealing said opening to form a closed system of said passageways containing such heat exchange fluid.

12. A method of making a plate-like second heat exchanger in heat exchange relationship with a first heat exchanger comprising sandwiching between pressure weldable surfaces of superimposed flat metal sheets a first pattern and a separate independent second pattern of stop-weld material, said first pattern being applied to define desired tubular passageways for flow of a first heat exchange fluid therethrough and said second pattern being applied to define a second system of tubular passages with said second system of tubular passages adapted to be formed into a closed system containing a second heat exchange fluid, pressure welding said sheets together in the areas not separated by said stop-weld material, forming an opening into the unwelded areas between said sheets defined by said second pattern of stop-weld material, applying to said opening a fluid pressure of sufficient magnitude to expand said unwelded area defined by said second pattern of stop-weld material, injecting through said opening said second heat exchange fluid to at least partially fill the expanded unwelded area defined by said second pattern, and sealing said opening to seal said second heat exchange fluid in said expanded unwelded area defined by said second pattern of stop-weld material.

13. The method of claim 12 wherein said second heat exchange fluid partially fills said expanded unwelded area defined by said second pattern of stop-weld material and wherein said second heat exchange fluid is vaporizable and condensable.
